CLAIM

I claim the ornamental design for the automotive lamp, as shown and described.

DESCRIPTION

FIG. 1 is a left side elevational view thereof;

FIG. 2 is a front elevational view thereof;

FIG. 3 is a right side elevational view thereof;

FIG. 4 is a top plan view thereof; and,

FIG. 5 is a bottom plan view.

The portion of the invention not shown in the drawings forms no part of the claimed design.
